BED-RAIL FASTENER.

1,316,113.

Specification of Letters Patent. Patented Sept. 16, 1919.

Application filed January 16, 1919. Serial No. 271,437.

To all whom it may concern:

Be it known that we, WENDELIN P. SENG and DARRELL F. DYKE, citizens of the United States, residing at Chicago, in the county 5 of Cook and State of Illinois, have invented a new and useful Bed-Rail Fastener, of which the following is a specification.

Our invention relates to bed-rail fasteners, more especially to that class thereof employed for connecting metal bed-rails to 10 wooden bed-posts.

The objects in view are to produce a fastener for the purpose mentioned capable of being stamped and folded from suitable gage 15 sheet-metal at a comparatively small cost, and which when in use, will constitute a rigid connection or fastening-means between the bed-rail and bed-post, and which will permit of ready disconnection and in the 20 typification shown, a reconnection for facilitating an end-for-end reversal of the rail.

Other objects and advantages of the invention will hereinafter appear, and the novel features thereof will be particularly 25 pointed out in the appended claims.

Referring to the drawing:

Figure 1 is a side elevation of a bed-rail provided with our improved rail-fastener, the latter being shown in its connected position with a wooden bed-post shown partly in section; and

Fig. 2 is a transverse vertical sectional view taken on the dotted line 2—2.

Similar numerals of reference indicate 35 similar parts in both figures of the drawing.

The post 1, may be of any design usually given wooden bed-posts, and at a suitable point has its face provided with a narrow vertical slot or kerf 2, intersected somewhat 40 below its middle by a cylindrical transversely disposed cross-pin 3. The bed-rail 4, is of the usual angle-iron construction and being well known, requires no particular description.

45 At each end of the bed-rail 4 is attached a sheet-metal fastener 5, and, as will be seen, each of such fasteners comprises a plate angular in cross-section and therefore consisting of the angularly disposed members 6 and 7. The latter member is merely an attaching-flange, being secured to the vertical web of the rail 4 by means of rivets 8, the 50 end of the rail abutting snugly against the companion member 6 of the fastener. The member 6, at a slight distance from the an-

gle of the plate, has its intermediate portion bent rearwardly and shaped to form in the example shown an arrow-shaped head 9, the same projecting beyond the remainder of the member upon which it is formed. This 60 head 9 at its inner side is provided with upper and lower slightly converging binding-edges 10 and 11, respectively, the head being connected to the member 6 by a reduced neck 12. The member 6, as before 65 indicated, is disposed at a right angle to the member 7, so that that portion thereof which lies between the angle of the fastener and the neck forms an abutment for the end of the bed-rail. Above and below the neck 12 70 the member 6 is shown as interiorly recessed to form opposite opposing hooks 13 and 14, respectively, these two hooks being preferably located at the same side of the vertical flange of the bed-rail and therefore 75 in longitudinal alinement.

In operation, in order to engage the rail to the post by means of the fastener, the head 9 of the latter is introduced into the upper end or portion of the slot or kerf 2 80 of the post and into engagement with the cross-pin 3. As the bed-rail is forced downward to its seat, the inclined edge 11, which is in engagement with the cross-pin 3, riding over the latter, serves to draw the 85 rail and its fastener snugly against the face of the post. The neck 12, or rather, that portion of the member 6 that is rearwardly bent to produce the neck, completely fills a portion of the length of the slot or kerf 2 90 of the post, the remaining portion of the slot or kerf being closed by the member 6 above and below the neck. In this manner an unsightly slot or opening in the post is 95 covered from view.

While the fastener as thus described, even with the omission of the hooks 13 and 14, will perform its function fairly well, and indeed, is practical, yet there is a certain amount of undesirable looseness present 100 owing to the fact that there is but one point of connection between the bed-post and bed-rail, namely, the pin 3 and head 9.

To fully overcome this we prefer to include the hooks 13 and 14. These we preferably locate at one side of the vertical flange of the rail and also in vertical alinement.

When the rail is first positioned, as heretofore described, and therefore, the rail-fastener is firmly seated upon the cross-pin 3, 110

- we insert into the wooden post within the hook 13, if the latter happens to be uppermost, a headed bolt or screw 15, the shank of which about agrees with the space within the hook. The head of the screw overlaps and engages the edge of the hook, but does not impinge thereupon with sufficient force to bind. It will thus be seen that irrespective of the presence of the headed screw 15, 10 the fastener may be raised from its position of engagement with the cross-pin and that such operation will also cause a disengagement of the upper hook with said screw. The rail may then be reversed end-for-end 15 so as to bring the horizontal web of the rail uppermost. That fastener formerly at the head of the bed will now become positioned at the foot of the bed and the lower hook 14 will now become the upper hook, but it 20 will be seen, will coöperate with the headed screw 15 as heretofore described. It will also be seen that the upper inclined shoulder 10 now becomes the lower shoulder and engages with the cross-pin 3. 25 By this arrangement, it will be seen that the fastener becomes braced against looseness and in fact a very rigid connection is produced out of one somewhat loose and for that reason not entirely satisfactory. 30 It will be seen that the fastener is capable of being integrally formed from a single blank of metal and at a comparatively slight cost. The flange 7 may be given any exterior decoration desired, and may be finished 35 and shaped as preferred and so as to accord with the design of post in connection with which it is to be used.
- Having described our invention, what we claim, is:
- 40 1. The combination, in a bed-rail fastener, of a bed-post provided with a vertical slot and a cross-pin, of an angular side-rail, a rail fastener angular in cross-section and having its front-member riveted to a flange 45 of the rail and its companion-member rearwardly disposed and shaped to form a head connected thereto by a neck and provided

with upper and lower oppositely inclined binding edges adapted to engage the cross-pin and above and below said neck recessed 50 to form hooks, and a headed member extending from said post and adapted to be removably engaged by said hooks.

2. The combination, in a bed-rail fastener, of a bed-post provided with a vertical slot 55 and a cross-pin, of an angular side-rail, a rail fastener angular in cross-section and having its front member riveted to a flange of the rail and its companion member rearwardly disposed and shaped to form a head 60 connected thereto by a neck and provided with upper and lower oppositely inclined binding edges adapted to engage the cross-pin and above and below said neck recessed 65 to form hooks disposed in vertical alinement at one side of the vertical flange of the rail and opposing each other, and a headed screw extending from the post and adapted to be removably engaged by said hooks.

3. The combination, in a bed-rail fastener, 70 of a bed-post provided with a vertical slot and a cross-pin, of an angular side-rail, and a rail fastener angular in cross section, said rail fastener having its front member secured to the rail and its companion member 75 rearwardly disposed at an intermediate point to form a connecting head provided with an inclined binding edge adapted to engage the cross-pin when said head is inserted and lowered within the slot, the said rear member of the fastener being provided with a hook at one side of and at an angle to the head, and a headed element projecting from the post and adapted to be engaged by the hook when said head is engaged by the said cross-pin. 80 85

In testimony whereof we have signed our names to this specification in the presence of two subscribing witnesses.
